UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

STATIC ELIMINATION SYSTEM.

Application filed November 16, 1921. Serial No. 515,581.

To all whom it may concern:

Be it known that I, JOSEPH SLEPIAN, a citizen of the United States, and a resident of Swissvale, in the county of Allegheny and State of Pennsylvania, have invented a new and useful Improvement in Static Elimination Systems, of which the following is a specification.

My invention relates to wireless receiving systems and more especially to tuning means particularly adapted for minimizing the effects of static disturbances.

In its broad aspect, the object of my invention is to provide a wireless receiving system embodying highly efficient means for eliminating disturbances tending to cause interference.

Another object of my invention is to provide a receiving system having such characteristics as to be selectively responsive to received signal impulses of predetermined frequency only.

A still further object of my invention is to provide a receiving system wherein such voltage-drops as are given by currents of value i may be balanced by voltages obtained by taking the double integral of said currents with respect to time.

Heretofore, various systems have been proposed embodying resonant-circuit arrangements tending to reduce interference between stations and to eliminate the undesirable effect of static impulses. However, such systems have proved only partially successful in that the resonant circuits embodied in such systems have a tendency to be set in oscillation by shock excitation, despite the utilization of various shielding schemes.

According to my invention, I provide means adapted to be utilized in any of the well known receiving systems, whereby the above mentioned defects may be minimized or entirely removed. The desired result may be obtained by including, in a local receiving conductor, a resistor having such value as to effectively damp the receiving system. Non-resonant means are then associated with said resistor, whereby the voltage-drop therein may be substantially neutralized for currents of predetermined frequency only, as explained more fully hereinafter.

These and other objects and applications of my invention, whereby my invention may be practiced, will be apparent from the following description and claims when read in connection with the accompanying drawing, wherein—

The single figure is a diagrammatic representation of a wireless receiving system embodying my invention.

In the drawing, an antenna 1 is connected to a ground conductor 2, through a tuning coil 3, a resistor 4 and a capacitive reactance device or condenser 5. Wave responsive apparatus 6, of well known form, may be operatively coupled to the antenna circuit through a coupling coil 7 and the tuning coil 3. The resistance of the resistor 4 is sufficient to rapidly damp disturbing electromotive forces having steep wave fronts, such, for example, as are found in a static impulse. The impedance of the condenser 5 is relatively small in comparison with that of the resistor 4.

A three-electrode tube 8 is shown as comprising an anode 9, a grid 11 and a hot cathode 12. The hot cathode 12 may be energized by means of a source of direct-current energy 13 through a resistor 14. A grid circuit for the tube 8 includes a primary winding 15 of a coupling transformer 16. A secondary winding 17 of the transformer 16 is connected around the resistor 4. The transformer 16 is so designed as to have a high self-inductance to received signal impulses.

A plate-filament circuit for the tube 8 comprises a source of direct-current energy 18, a resistor 19, a capacitive reactance device or condenser 21 and a radio-frequency choke coil 22 which is connected in shunt to said condenser. The internal impedance of the tube 8 is regarded as being embodied in the resistor 19.

A second three-electrode tube 22 is shown as comprising an anode 23, a controlling grid 24 and a hot cathode 25, the latter being energized from a source of direct-current energy 26 through a resistor 27. The potential variations across the terminals of the condenser 21 are impressed upon the input electrodes 24 and 25 of the tube 22 by means of conductors 28 and 29, respectively.

A plate-filament circuit for the tube 22 comprises a resistor 31, a source of direct-current energy 32, and the condenser 5 shunted by a radio-frequency choke coil 33. 5 Here again, the resistor 31 includes the internal impedance of the tube 22.

Upon the receipt of sustained signal impulses, the potential-drop across the resistor 4 is impressed upon the input electrodes 11 and 12 of the tube 8, thereby causing currents of value i_1 to traverse the plate-filament circuit of the tube 8. These currents are determined by the relation

$$15 \quad i_1 = \frac{\mu_1 R_i}{R_1},$$

where μ_1 is the voltage factor of the tube 8, R is the resistance of resistor 4, i is the current through the resistor 4 and R_1 is the resistance of the resistor 19. The capacitance of condenser 21 is so chosen that the currents in the plate-filament circuit of the tube 8 are practically determined by the resistance of resistor 19. Therefore, the reactance of the condenser 21 need not be considered in the above equation.

The voltage-drop e_1 across the condenser 21 is determined by the relation

$$30 \quad e_1 = \frac{1}{C_1} \int i_1 dt = \frac{\mu_1 R}{C_1 R_1} \int idt$$

where C_1 is the capacitance of the condenser 21.

35 The voltage e_1 is applied to the grid of the tube 22, thereby causing a voltage drop across the condenser 5 which is given by the relation

$$40 \quad e_2 = \frac{1}{C_2} \int i_2 dt = \frac{1}{C_2} \int \frac{\mu_2 e_1}{R_2} dt \\ = \frac{\mu_1 \mu_2 R}{C_1 C_2 R_1 R_2} \int \int idt dt$$

45 where C_2 is the capacitance of the condenser 5, i_2 is the current in the plate-filament circuit of the tube 22, μ_2 is the voltage factor of the tube 22 and R_2 is the resistance of the resistor 31.

50 Assuming the desired signal impulse currents are of the form $i = A \sin pt$, then

$$\int \int idt dt = -\frac{A}{p^2} \sin pt$$

55 Substituting this value in the equation for e_2 , it is found that

$$60 \quad e_2 = -\frac{\mu_1 \mu_2 R A}{C_1 C_2 R_1 R_2 p^2} \sin pt$$

65 The several constants may be so adjusted that the voltage-drop across the condenser 5 is equal and opposite to that across the resistor 4. Hence, the voltage drop in the antenna circuit between points 33 and 34,

or across the resistor 4 and condenser 5, will be zero, and we have the equation:—

$$1 - \frac{\mu_1 \mu_2}{C_1 C_2 R_1 R_2 p^2} = 0 \quad 70$$

In view of the foregoing, it may readily be seen that, when the constants of the tube circuits are so adjusted that

$$\frac{\mu_1 \mu_2}{C_1 C_2 R_1 R_2} = p^2 \quad 75$$

the voltage-drop across the condenser 5 just balances the voltage drop across the resistor 4, thus nullifying the impedance of the resistor 4 to the currents having the desired 80 frequency. For currents of other frequencies, the resistor 4 becomes effective to damp out the disturbing impulses.

An advantage of my invention is the provision of a static elimination system 85 having no resonant elements, such as would be set in oscillation by static impulses.

While I have shown only one embodiment of my invention in the appended drawing, it is capable of various modifications and changes without departing from the spirit of my invention and I desire, therefore, that only such limitations shall be imposed thereon as are demanded by the prior art or by the appended claims. 95

I claim as my invention:

1. In an electrical system, a circuit carrying currents, an impedance device and a capacitive reactance device in series-circuit relation thereto and means responsive to the potential-drop across said impedance device for impressing such modified currents across said capacitive device that the voltage-drops across said devices nullify one another. 100

2. In an electrical system, a circuit carrying periodically varying currents, a resistor device and a capacitive-reactance device included in series-circuit relation thereto, said resistor having a relatively high impedance in comparison with said reactance device, and means responsive to the potential-drop across said resistor for impressing amplified currents across said capacitive device, said last-mentioned currents having such characteristics as to cause the voltages across said devices to balance. 110

3. In a wireless receiving system, a receiving circuit including a resistor and a capacitive reactance device, said resistor having such resistance as to effectively screen the system from static disturbances, and means selectively responsive to currents of predetermined frequency in said receiving-circuit, whereby the voltage-drop across said resistor may be balanced by an opposite voltage-drop across said capacitive reactance device. 120

4. In an electrical system, a circuit carrying currents of predetermined frequency and apparatus associated therewith selec- 130

- tively responsive to currents of said frequency, said apparatus comprising a high-resistance resistor and a relatively low-impedance capacitive reactor serially included in said circuit, and means associated with said resistor and with said reactor for causing the potential-drops across said resistor and reactor to be balanced for currents of said predetermined frequency only.
- 10 5. In an electrical system, a pair of three-electrode tubes having input and output circuits, the output circuit of one tube being interlinked with the input circuit of the remaining tube, a high-impedance element included in the input circuit of said first-mentioned tube, a relatively low-impedance element included in the output circuit of said second-mentioned tube and a work circuit including said impedance elements 15 20 in series relation, the constants of said input and output circuits being such that, for currents of predetermined frequency in said work circuit, the voltage-drop across said high-impedance element caused by said currents is balanced by an opposite voltage-drop across said low-impedance element.
6. In an electrical system, a pair of three-electrode tubes having aperiodic input and output circuits, the output circuit of one tube being electro-statically interlinked with the input circuit of the remaining tube, a high-impedance resistor element included in the input circuit of said first-mentioned tube, a relatively low-impedance capacitive 30 35 reactance element included in the output circuit of said second mentioned tube and a work circuit serially including said elements, the constants of said input and output circuits being such that, for currents of predetermined frequency in said work circuit, the voltage-drop across said resistor caused by said currents is balanced by an opposite voltage-drop across said capacitive element.
- 40 45 7. In a wireless receiving system, a pair of three-electrode tubes having aperiodic input and output circuits, the output circuit of one tube being electro-statically interlinked with the input circuit of the remaining tube, a resistor included in the input circuit of said first-mentioned tube, a capacitive reactance device included in the output circuit of said second-mentioned tube, said device having a low-impedance relative to 50 55 that of said resistor, and a receiving conductor serially including said resistor and said device, the constants of said input and output circuits being such that, for currents of predetermined frequency in said receiving conductor, the voltage-drop across said resistor caused by said currents is balanced by an opposite voltage-drop across said capacitive device, and said resistor having such resistance as to effectively damp 60 65 the receiving conductor with respect to currents differing from said currents of predetermined frequency.
8. In an electrical system, a three-electrode tube having plate-filament and grid-filament circuits, said latter circuit including a resistor of value R , said former circuit having a resistance of value R_1 and including a capacitive reactance device of value C_1 , a second three-electrode tube having plate-filament and grid-filament circuits, said latter grid-filament circuit including said capacitive reactance device, said latter plate-filament circuit having a resistance of value R_2 and including a capacitive reactance device of value C_2 , and a 70 75 80 circuit serially including said resistor and said last-mentioned reactance device, the constants being adapted to be so adjusted that the potential-drops across said resistor and said device are substantially balanced 85 when currents of substantially the form $i = A \sin pt$ traverse said latter circuit.
9. In a wireless receiving system, a receiving conductor adapted to carry currents of substantially the form $i = A \sin pt$ and including a resistor of value R and a capacitive reactance device of value C_2 , a three-electrode tube having a voltage factor μ_1 operatively associated with said resistor and responsive to the potential drop there-across upon the receipt of impulses, a plate-filament circuit for said tube having a resistance of value R_1 and a capacitive reactance device of value C_1 , a second three-electrode tube having a voltage factor μ_2 operatively associated with said plate-filament circuit and responsive to potential variations across said last-mentioned reactance device, a plate-filament circuit for said second tube including a resistance of value R_2 90 95 100 and said capacitive reactance device of value C_2 .
10. The method of tuning which consists in balancing potentials of value $f(x)$ against potentials of value $A \int \int f(x) dx dx$, 110 where $f(x)$ is a given function of a given variable quantity x , proportional to time, and A is a constant.
11. The method of tuning which consists in balancing voltages given by currents of value i against voltages obtained by taking the double integral of said currents with respect to time.
12. In connection with a wireless receiving system including a receiving conductor having a resistance of such value as to effectively screen the system from static disturbances, the method of producing, in said conductor, a negative-resistance reaction of such value as to compensate for losses 115 120 125 caused by currents of predetermined frequency in said resistance which consists in impressing upon said conductor voltages obtained by taking the double integral of said currents with respect to time.

13. The combination with a circuit adapted to be energized from a desired source of periodic voltages of a given frequency and also from an undesired source of voltages of different nature, of a series-connected damping resistor and non-resonant current-responsive means for impressing on said circuit a voltage of such nature as to substan-

tially neutralize the voltage-drop across said resistor with respect to desired currents but not with respect to undesired currents. ¹⁰

In testimony whereof, I have hereunto subscribed my name this 31st day of October, 1921.

JOSEPH SLEPIAN.
